ASSIGNMENTS, TO JAPANESE TISSUE MILLS, OF HOLYOKE, MASSACHUSETTS,
A CORPORATION OF MASSACHUSETTS.

PACKAGE.

1,302,116.

Specification of Letters Patent. Patented Apr. 29, 1919.

Application filed April 30, 1917. Serial No. 165,408.

To all whom it may concern:

Be it known that I, COURTNEY P. WINTER, a citizen of the United States of America, residing at Holyoke, in the county of Hampden and State of Massachusetts, have invented certain new and useful Improvements in Packages, of which the following is a specification.

This invention relates to an improved package of articles, such as napkins, towels, and the like and more particularly paper napkins and towels.

An object of the invention is to provide a package of articles, such as paper napkins, for example, which consists of a stack of superimposed articles, each of which is folded in triangular form with upper and lower folds, the former being shorter than the latter for the purpose of permitting the upper article in the package to be grasped and picked up without touching the article therebelow.

Other objects and advantages will appear in the description to follow and will be particularly pointed out in the appended claims.

The invention, in an embodiment at present preferred, is shown for illustrative purposes in the accompanying drawings, in which—

30 Figure 1 is a perspective view of a fixture showing a conventional representation of the package therein; and

Fig. 2 is a plan view of the package shown, as removed from the fixture.

35 The package, represented generally by reference letter *a* in Fig. 1, is substantially triangular in shape. It consists of a plurality of vertically stacked articles, each of which is folded in the manner best shown in Fig. 2.

40 The articles, for example, paper napkins, are substantially rectangular sheets each of which may be folded one or more times upon itself in the usual manner, the folded article still retaining its rectangular shape. The 45 rectangular napkin, or the rectangularly folded napkin, is folded along a line *b* which is substantially parallel with but is spaced from one of the diagonals of the rectangular article. This folding operation divides the

50 napkin into two parts *c* and *d*, and the former is superimposed upon the latter, as shown in Fig. 2. The part *c* or upper fold of the napkin is of triangular shape, and the part *d* or lower fold is substantially tri-

angular although not exactly so since the line of fold *b* is not a diagonal of the rectangularly shaped napkin. The fact that line *b* parallels but is spaced from the diagonal line of the napkin results in making one fold, the upper fold *c*, smaller than the fold *d* therebelow, so that two edges of the former parallel the corresponding edges of the latter and are spaced therefrom toward the line of fold *b*. The package, as has been mentioned, comprises a plurality of napkins, each folded as described, which are stacked one upon another with the short fold *c* uppermost. The napkins, thus stacked into package form, may be held temporarily together in any suitable manner, as by elastic bands, for example.

The described package is intended to be used with a dispensing fixture such for example as is shown in Fig. 1. This fixture involves two vertically upstanding members 5, each of which is of the shape of an inverted U. The members 5 are arranged in spaced parallel relation and the rear leg of each is connected with a horizontal portion 6. The latter is spaced forwardly from the common vertical plane of the rear legs of member 5 by the bent portions 7, one adjacent the bottom of each rear leg of members 5. The horizontal member 6 is also spaced vertically above the lower ends of members 7. The front legs of the members 5 are also connected by portions 8, 9, and 10. The portions 8 are inwardly turned toward one another from their respective legs of member 5, and the portions 9 are bent forwardly at right angles to the members 8 and lie in spaced parallel relation. The members 8 and 9 all lie in a common horizontal plane and in the same horizontal plane as the described member 6. The spaced forward ends 85 of the members 9 are connected by a U-shaped portion 10 which is bent downwardly at right angles to the members, as clearly shown. The two portions 7 and the portion 10 are adapted for supporting engagement 95 with a table, counter, or other suitable supporting means.

It will be seen that the bottom of the package is supported along its rear edge by the member 6, intermediate its rear edge and its forward pointed corner by the members 8, and the pointed corner is supported by the member 9. The lowermost napkin in pack

age *a* is held away from the supporting means for the fixture by the leg-forming portions 7 and 10. The two pointed side corners of the package are received between the 5 inverted U-shaped members 5 and slidable on the latter are weights 11.

It is to be noted that the spaced parallel upright loop forming members 5 function to position the package *a* and hold it against 10 displacement in any direction in a horizontal plane. The package cannot be moved an appreciable distance to the right or left or forwardly or rearwardly without being arrested by abutment with some part of members 5. The weights 11 serve to hold the package upon its described bottom supporting means and compress the package to some degree adjacent its side corners. The central portion of the package is not, however, 15 compressed and the compression of the side portions of the package has a tendency to throw the forward triangular corners of the package upwardly and to separate the triangular corners of the upper folds *c* from the 20 lower folds *d*.

The forward triangular corner of the upper fold *c* is thus ordinarily positioned slightly above the lower fold *d* and constitutes the only part of the napkin which is 25 conveniently available to be grasped. By being positioned in such a manner, the forward corner of fold *c* is so temptingly arranged for convenient grasping that one involuntarily reaches for this corner when 30 it is desired to withdraw a napkin from the fixture. One naturally grasps the napkin by the forward corner of upper fold *c* and in so doing only the upper napkin itself is touched. The napkins therebelow are 35 protected from contact by the projecting lower fold *d*. The package is also arranged so that only one napkin at a time can be conveniently withdrawn.

In use, the forward triangular corner of 40 the upper fold *c* of the uppermost napkin of package *a* is grasped and drawn forwardly. The triangular edges *e* of the lower fold *d* are brought into engagement with the forward legs of members 5. On continued 45 movement of the napkin forwardly, the edges *e* act against the forward legs of member 5 with a cam action to force the two side portions of the upper napkin inwardly toward one another and this results in forcing the central portion of the napkin upwardly. Upon further forward movement, the central portion of the napkin is bent upwardly to such an extent that its side edges 55 clear the forward legs of members 5 so that the napkin may be withdrawn. To put the matter another way, the triangular fold provides the two diverging cam-edges *e*, *e*, 60 for coöperation, with the spaced abutments or buckling members of the dispenser, 65 whereby the napkin is buckled as it is drawn

forward, thereby to free the napkin being withdrawn from the one next below. Now it will be noted that as the withdrawing continues, the natural tendency of the operator is to increase the speed, the withdrawing 70 action becoming almost a snatch. And here the cam action is of peculiar value, for, as the withdrawing continues the buckling progressively increases and the surface freed from the napkin below progressively increases, so that although the speed of withdrawal increases, the tendency for the lower napkin to be pulled out because of its adhesion to the one above progressively diminishes. 75

It is to be noted particularly that the weights 11 play an important part in the withdrawing of napkins in the described manner. They not only act in the ordinary way to hold the package upon its supporting members, as described, but they also function to hold the rear edge of the napkin from being drawn upwardly to defeat the smooth withdrawal of the napkin by the described cam action. For example, a 80 forward pull on the forward corner of fold *c* acts on lower fold *d* at the rear thereof along the line of fold *b*, and the edges *e*, being held by abutment with the forward legs of member 5 hold the lower fold *d* 85 against forward movement with result that without the weights 11 the unrestrained rear edge of the napkin will be drawn forwardly and lifted vertically before the described cam action can occur. This brings 90 a relatively large surface of the napkin against the forward legs of members 5 rather than thin edges as when the rear edge of the napkin is restrained from lifting by the weights 11. 95

Thus, an improved package of napkins or the like has been provided which is characterized by its arrangement, whereby only one napkin at a time can be picked up 100 and that one picked up without touching 105 the napkins therebelow.

The invention has been described in a form at present preferred for the purposes of illustration, but the scope of the invention is defined by the appended claims rather 110 than by the foregoing description.

What I claim is—

1. As an element of a dispensing fixture having buckling members, a package 115 of paper articles to be drawn between said buckling members, said package comprising a plurality of articles folded into substantially triangular form, thereby to present diverging cam edges for coöperation with the buckling members of the fixture, and 120 whereby, upon withdrawal of an article, said edges are adapted for coöperation with the buckling members to free said article from the next, each of said articles being 125 folded to produce upper and lower substan- 130

tially triangular parts of which the upper is shorter than the lower, whereby the top article of the stack may be removed therefrom by grasping the short upper fold without touching the napkin therebelow.

2. As an element of a dispensing fixture having buckling members, a package of paper articles to be drawn between said buckling members, said package comprising a plurality of articles folded into substantially triangular form, thereby to present diverging cam edges for coöperation with the buckling members of the fixture, and whereby, upon withdrawal of an article, said edges are adapted for coöperation with the buckling members to free said article from

the next, said articles being rectangular and folded along a line parallel with but spaced from a diagonal of the article to form upper and lower substantially triangular parts, 20 the edges of the upper being in spaced parallel relation with the corresponding edges of the lower part except for the common line of fold so that the lower protrudes beyond the upper part, said articles being superimposed one upon another into stack form, whereby a package for dispensing purposes is provided in which the upper article may be removed by means of its upper part without touching the article therebelow.

COURTNEY P. WINTER.
